(21) Appl. No.: **29/262,335**

(57) **CLAIM**

(22) Filed: **Jun. 30, 2006**

The ornamental design for a track mounted ballast box with rotatable bracket arm, as shown and described.

(51) **LOC (8) Cl. 26-99**

DESCRIPTION

(52) **U.S. Cl. D26/138**

FIG. 1 is a slightly enlarged oblique view of the track mounted ballast box with rotatable bracket arm of the instant invention.

(58) **Field of Classification Search D26/24,**

FIG. 2 is a top view of the instant invention.

D26/72, 80, 81, 82, 83, 85, 86, 88, 94, 102,

FIG. 3 is one side view of the instant invention. The opposite side view is the mirror image.

D26/113, 118, 122, 123, 128, 138, 140, 143,

FIG. 4 is the bottom view of the instant invention.

D26/152, 155, 156; 362/147, 148, 150, 640,

FIG. 5 is one end view of the instant invention; and,

362/647, 648, 649, 257, 317, 326, 331, 336,

FIG. 6 is the opposite end view of the instant invention.

362/337, 339

The broken line showing is included for the purpose of illustration only and forms no part of the claimed design.

See application file for complete search history.
